DESIGN FOR A MEAT SLICING MACHINE OR SIMILAR ARTICLE

Thomas L. Hand, Cincinnati, Ohio, assignor to
The Cincinnati Time Recorder Company, Cincinnati, Ohio, a corporation of Ohio

Application May 16, 1938, Serial No. 77,202

Term of patent 14 years

To all whom it may concern:

Be it known that I, Thomas L. Hand, a citizen of the United States and a resident of Cincinnati, in the county of Hamilton and State of Ohio, have invented a new, original, and ornamental Design for a Meat Slicing Machine or Similar Article, of which the following is a specification, reference being had to the accompanying drawing forming part thereof.

In the drawing:

side of the meat slicing machine or similar article embodying my design.

I claim:

The ornamental design for a meat slicing machine or similar article, substantially as shown.

THOMAS L. HAND.
